Lackenbach Siegel, LLP(57) **CLAIM**

The ornamental design for a butter container, as shown and described.

DESCRIPTION

FIG. 1 is a top perspective view of a butter container, showing my new design;

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines represent portions of butter container, which form no part of the claimed design. The circular broken lines, adjacent to the claimed subject matter in FIG. 7, represent a boundary line which forms no part of the claimed design. None of the broken lines form part of the claimed design.
